Application September 27, 1949, Serial No. 118,076

6 Claims. (Cl. 20—1.4)

2

Another object of the invention is to form the dome or roof of the silo in four sections, each of which is supported on a horizontal laminated member that rests on the inverted channel and fastened thereto by suitable up-right lengths which four roof sections are suitably joined together on radial seams, and are fastened to the laminated sections by metal brackets.

These and other objects of the invention will be illustrated in the drawings, described in the specification and 10 pointed out in the claims at the end thereof.

In the drawings:

Figure 1 is a side elevation of the silo with a large section taken out near the top of the figure.

Figure 2 is a detail view of the dowel pin used for 15 joining the staves together.

Figure 3 is a horizontal section showing two staves held together by the dowel pin.

Figure 4 is a vertical section showing how the tops of 20 the staves are joined together in a circle and how they support the roof.

Figure 5 is an upright section on the line 5x, 5x of Figure 6 showing the bracket by which the upright staves are joined to the concrete foundation.

Figure 6 is a front elevation of the bracket and staves 25 shown in combination in Figure 5.

Figure 7 is a front elevation of the door opening and the foundation of the silo, two of the lowest doors and a part of the third door being shown.

Figure 8 is a horizontal section on the line 8x, 8x of 30 Figure 1 looking at it from the right hand side of Figure 1, the chute being shown partly broken away and the door posts being shown in their original position; namely, closest together with the opening between them, which opening is closed by the door in its normal or closed position.

Figure 8a is a detail view of the turn buckle.

Figure 9 is a horizontal section on the same line 8x, 8x of Figure 1, showing the door posts drawn apart by the 35 hoops and nuts thus enlarging the opening with the doors in their normal position still closing the enlarged opening.

Figure 10 is a diagrammatic view showing the doors and the links for supporting them in side elevation looking to the left from the section line 10x, 10x of Figure 8 with the intervening portion of the silo structure omitted from the drawing.

Figure 11 shows the top and bottom horizontal angle 45 irons that connect the upright links together, which links support the door; the details of the doors and supports therefore partially appear on the right of Figure 1 at the bottom, the upper doors etc. being concealed by the chute.

Figure 12 is a top plan view of the coupling that holds the rear ends of the hoops together, which couplings are shown on the left of Figure 1.

Figure 13 is a section taken on the line 13x, 13x of Figure 12.

Figure 14 is a top plan view of the roof, and the dormer windows.

Figure 15 shows an elevation of the dormer window on the left hand side of the roof of the silo looking at it from the left.

Figure 16 shows one of two sections of the roof looking at it from below.

Figure 17 is a section on the line 17x, 17x of Figure 14 showing how the four sections of the roof are bolted together from the outside.

In the several figures of the drawings, like reference numerals indicate like parts.

In the drawings reference numeral 1 indicates the concrete foundation which foundation has a bottom 2 and an upright circular wall 3. The top of the circular wall is cut off at an angle of forty-five degrees sloping down and 70 to one of the upright staves.

out from the inside of the wall. In the circular wall 3 are molded the studs 4. On top of this beveled circular wall is held the upright staves 5, the bottoms of which staves are cut at a thirty degree angle. This angular finish of both the upright wall and the bottom of the staves is used for the purpose of giving good drainage between the upright staves and the concrete wall so that the bottom of the staves will be kept as dry as possible.

The bottoms of the staves rest on the beveled edge of the concrete wall below the top corner of the concrete wall, so that the concrete wall serves as a backing for the ring of staves that is erected on it. The triangular space between the back of the staves and the top edge of the wall can be filled in with any plastic material as is indicated by reference numeral 6. These details are all shown in Figure 5, of the drawings.

At regular intervals a metal strap 7 is fastened to two or more of the upright staves. This strap is engaged by a bracket 8, which is perforated at the bottom through which perforations extends a stud or bolt 4. This stud is connected to the bracket 8 by the nut 9 so that the staves at regular intervals are positively held down on the foundation wall 3.

The staves are joined together radially with a tongue and groove joint as shown in horizontal section in Figure 3. The staves are about six inches wide. The edges of the staves are cut radial to the diameter of the silo so that when the staves are joined together they form a circle. At regular intervals from top to bottom, the staves are joined together circumferentially by metal dowel pins 10 such as are shown in Figures 2 and 3. These dowel pins also hold the staves from working up and down on each other. These dowel pins are made of metal and on each end are formed with barbed cones. The staves are bored with holes having a diameter that corresponds to the intermediate section 11 of the dowel pin, and when the dowel pins are driven into the staves, they take a firm hold thereon. These staves are assembled in a ring around the silo and are held in place in a cylinder by the hoops 12 which together with their attachments encircle the silo as will presently be described. Each of these hoops comprises two members 12a and 12b. At the rear end the ends of these members are swedged up as indicated at 13a and 13b. These members are joined together by a rectangular coupling 15 shown in Figure 12. The end walls of this coupling are perforated as indicated at 16 so that the members 12a and 12b can be passed through the openings in the end walls of the couplings. The members 12a and 12b are then drawn into the upper slot shown in Figure 13 and the swedged end is jammed into the hole by which it is firmly held in place.

One side 17 of the coupling is formed to one radius and the other side 18 is formed to another radius, the idea being that one side 17 is applied to the silo having a radius of seven feet, and the other side 18 being applied to a silo having a radius of six feet, or any other radius that might be used in standard construction.

The coupling in one instance is applied as shown in Figures 12 and 13 with the side 17 against the silo and in the other instance is applied with the side 18 against the silo, but the position of the coupling is then reversed from end to end, so that the curved end 20 as shown in Figure 13 will always be down to the silo instead of up to the silo. These couplings 15, 15 form a ladder to the filling opening at the top of the silo.

Silos are frequently built to the height of thirty feet or more. It would be desirable to use staves the length of which would correspond to the heights of the silo, but lumber of that length is not easily found and it is therefore desirable to use staves having for example a length of ten and twenty feet or twelve and eighteen feet, etc., the two pieces of the staves being joined together end to end by a joint 21 as shown in Figure 13, to make one thirty foot stave.

The dowels 10 are used to join the staves together both above and below the joints 21. If the silo is thirty feet high and the staves are twelve feet and eighteen feet in length, there will be two rings of joints 21 and 21a as is shown in Figure 1, and in such case there will be used at least five rings of dowel pins such as is shown in Figure 3 and there will be one dowel pin in each ring for each stave. These rings of dowel pins will be located, substantially as follows. In a thirty foot silo the lowest ring will be about two feet above the foundation, the second ring will be about two feet below the ring 21 in Figure 1, the third ring will be about midway between the rings of joints 21 and 21a, the fourth ring will be two feet above the ring 21a and the fifth ring will be two feet from the top of the stave or twenty-eight feet from the bottom. In addition, the staves will be held together by the hoops which hoops have been partially described above. The hoops comprise the two members 12a and 12b and the coupling 15, which coupling is placed at the back of the silo. These hoops are joined together at the front of the silo by a turn buckle that will now be described. This turn buckle is shown separately in Figure 8a.

In a silo that is fourteen feet in diameter, the total length of each hoop and couplings would be about forty-four feet. The coupling 15 at the back would be about one foot long and the members 12a and 12b would each be about twenty-one (21) feet long. About eighteen inches of the forward end of each of these two members would be made of stock about one-eighth inch thicker than the balance of the member. That is to say, if the member were made of one-half inch round stock about eighteen inches of round stock five-eighths inches in diameter would be welded on to the end of it and this large end of eighteen inches would be threaded as shown at 25a and 25b in Figures 8 and 9. These threaded ends 25a and 25b are connected by a turnbuckle 26 which turnbuckle is separately shown in Figure 8a and is shown in combination in Figures 8 and 9. The ends of the turnbuckle engage the threaded ends 25a and 25b of the members 12a and 12b and the turnbuckle is turned to draw these members together so that the hoop as a whole is drawn tightly around the staves.

It will also be understood that one of the threads will be a right hand thread and the other will be a left hand thread so that the two members will be drawn together as the turnbuckle is turned.

It will also be understood that the turnbuckle is located in front of the door opening, and the length of the turnbuckle is less than the opening between the door posts 27a and 27b; namely, about twenty inches.

It will also be understood that the member 12a passes through the door post 27a and the member 12b passes through the door post 27b.

On the threads 25a and 25b nuts 28a and 28b are placed, which when turned draw the posts firmly against the staves and tends to enlarge the door opening and as the turnbuckle 26 is turned, it tends to close the door opening and make a stable structure of the desired diameter.

It will be understood that there is one hoop for every door or one door for every hoop that encircles the silo except the bottom hoop. The door 35 is shown in top plan view in Figures 8 and 9. On each door there are two cleats 36a and 36b. Pivotal mounted on the hubs of the turnbuckle are the links 37a and 37b. Each of these links is C-shaped and has eyes 38a and (38b) at the top where they engage the hubs of the turnbuckle. They extend outwardly from the doorway as indicated at 39a and 39b and then down as indicated at 40a and 40b and then inwardly as indicated at 41a and 41b inwardly toward the doorway and then laterally across the doorway as indicated at 42a and 42b. The lateral extensions 42a and 42b engage in slots 43a and 43b in the cleats 36a and 36b. These links are about one-half inch in diameter and the slots 43a and 43b are about three inches

long. When each door is closed it rests directly on the door below it, making a tight fit with the lower door. For this purpose each door is cut away to make a ship lap joint as indicated at 45 in Figure 10. The eyes 38a and 38b of each link are pivoted on the hubs of the turnbuckle and the turnbuckle is supported on the threaded end of the hoop.

It will be assumed that the door is about two feet high and the ensilage will be removed from back of the door as far down as may be necessary. The top of the door will be swung backward around the bottom of the door as a center carrying with it the lower ends 42a and 42b of the links. The lower ends 42a and 42b of the links will travel up slightly in the slots 43a and 43b. When the top of the door gets back far enough, the door can be moved up endwise and the middle of the door and the bottom of the links will then swing in a circle of which the hub of the turnbuckle is the center and the door can then be placed in the horizontal position indicated by dotted lines in Figure 10, and from there it can be swung to the upright upside down position shown by dotted lines at the top of Figure 10. In Figure 10 the top door is shown in dotted lines in an inverted position. Fastened to the frame of the dormer roof at the top of the chute on the right of Figure 1 is a hook 47 which engages the top door and holds it up in the dotted line position shown in Figure 10.

On the top door shown in full lines in Figure 10 is a hook 48. When this door is swung up to its dotted line inverted position, this hook 48 will engage with the next door below it when it is swung up to the inverted position. The next door below it is indicated at 35 and is engaged at the top with the hook 48, after it has been swung up to the broken line position shown in Figure 10. In like manner each door will be swung up to this position as the ensilage is removed from the silo, and the level of the ensilage falls to correspond.

As will be seen in Figures 8 and 9, the top of the door is shown in both figures in solid lines and the back of the door 35 is much wider than the front of the door and the side edges of the doors are beveled and the backs of the door posts 27a and 27b are beveled to nearly correspond and the outer edges of the beveled sides of the door rest against the beveled backs of the door posts and make a close fit therewith, whether the door posts are closer together as shown in Figure 8 or are spread apart as is shown in Figure 9.

To secure this result the bevels on the door are made slightly out of line with the bevels on the door posts.

It will thus be seen that the doors rest closely against the door posts and will securely close the door opening or doorway at the front of the silo regardless of whether the position of the door post has been altered much or little.

It will also be understood that an ordinary turnbuckle has two hubs rigidly connected together by two sides of links which enclose a rectangular space between. But the turnbuckle that I use, which is shown in Figures 8, 8a and 9 omits one of these sides or links. The turnbuckle is made in this way, so that it will not obstruct the cleats on the doors as the doors move to their outermost position as is shown in Figure 9. It will be assumed that the clearance between the inside of the hubs of the turnbuckle is about fourteen inches and the threaded ends of the hoops project into this space an inch or so as shown in Figures 8 and 9. The cleats will be placed on each door so that when the door is in its outermost position radially as shown in Figure 9, these cleats can extend into the open space between the threaded ends of the hoops, which threaded ends may be less than ten inches apart.

Between the links 37a and 37b, I fasten the angle irons 50 and 51 which serve as rungs of a ladder, two of these angle irons being provided on the links of each door. See Figures 7 and 11.

As shown in Figures 1 and 8 and 9, I provide a chute 53 on one side of the silo. This chute encloses the doors shown in Figures 8 and 9 so that, if the wind blows, the ensilage will fall straight down in a pile. This chute is fastened to hoops 12a and 12b by brackets 54a and 54b, which brackets consists of a metal strap that goes around the hoop and the two ends are brought together and given a quarter turn, which can then be bolted to the frame of the chute.

10 It will also be understood that after the silo has been built some years, the staves will shrink and it will then be necessary to turn the nuts 28a and 28b so as to spread the door posts 27a and 27b apart and take up the shrinkage and tighten up the staves against the hoops. In this 15 way the silo will be held to substantially the same diameter throughout and will always fit the base and the roof will always fit the top.

In Figure 4 the tops of the staves 5 are shown. After the silo has been finished up to the point an inverted 20 channel 60 is built on top of the staves clear around the silo in a complete circle. Where this channel encloses the tops of the door posts, the tops of the door posts are cut away to conform to the thickness of the staves. This channel is made up of five members, one member 25 on the inside about one inch thick and eight inches high or wide. Next is placed two intermediate members, each about one inch thick and about four inches high and on the outside two members eight inches high or wide are placed each about one inch thick. These members 30 are all shown in cross section in Figure 4 and are bolted together by a series of bolts 65. At suitable intervals straps 66 are used which are pivoted on the bolts 65 and bolted to the staves at 67. These straps 66 are morticed into the inside of the channel, the mortice being wider 35 than the straps 66. This construction permits the tops of the staves to move sideways in the channel.

The roof of the silo and its sill rests on this channel and is attached to it. The construction of the roof and its sill will now be described.

40 As shown in Figures 1 and 14 the roof 70 of the silo is substantially a dome or a half of a sphere. It is made up in four sections 71, 72, 73 and 74. These sections are preferably interchangeable. The section 72 has a dormer roof 72a built therein to cover the top of the 45 chute 53. The section 74 has a dormer window 74a built therein to provide for a filling opening. This dormer has a roof 75 made in two sections 75a and 75b which are symmetrically alike. These sections are hinged on the side at 76a and 76b. Each section of the dormer roof can swing on its hinge outward as shown in dotted lines near the top of Figure 15. This uncovers an opening near the top of the dome through which the silo can be filled from above instead of from the side. This allows easy filling of the dome of the silo giving greater

50 capacity. The two halves of the roof of the dormer will be closed with an overlapping joint. Each of these four sections of the roof is built in the shop or factory and each section includes a sill 80 and rafters 81 and 82. These rafters are joined together at the top by a 55 corner bracket 83 as appears at the bottom of Figure 16.

Each section of the roof is covered with a metal plate 84, which plate on the edges of the section is first bent up and then down on itself so as to form a flange 85 outside of the roof and an angle 86 inside of the roof 60 in which angle the wooden rafter 81 or 82 is fastened. When the sections are brought together the flanges 85 outside of the roof will lie side by side and will be covered with a metal channel 87. Through this channel and the flanges, bolts will be drawn which will draw the channel and the flanges close together and make a rigid leak proof construction. When the sections of the roof are ready to be assembled on top of the silo, metal straps 88 will be used to join the sills 80 to the channel 60. The sill 80 will preferably be made of several laminations which will extend preferably up and down, and the

rafters will be laminated in like manner, but in the rafters, the laminations will preferably be horizontal. The sill 80 is fastened to the metal roof section by brackets 80a, Figure 4.

It will also be understood that suitable construction of rafters will be extended up from the sill to support the dormer window 74a.

It will also be understood that a suitable sill 90 indicated by dotted lines in Figure 14 is formed on the under side of the dormer roof 72a to fit the top of the chute 53 and the dormer roof 72a will be welded to the roof of the section 72.

A hole 91 is provided at the top which can be covered with any suitable form of ventilator. A ladder 94 will be built on the dome preferably at the side of the dormer 74a, and this ladder should be placed so that it is accessible from the ladder formed by the rectangular couplings 15 shown in Figure 12 regardless of the position of the dormer.

It will also be understood that the sections of the dome shown in Figure 14 can be assembled in any order that may be desired. The section 72 with the dormer roof 72a must always be placed over the discharge chute. The section 74 having the filling dormer window can be located in any of the three remaining places.

Having thus described the details of the construction, I will now describe the assembling of the silo in a more general way.

First the foundation is laid with studs 4 set upright therein. The door posts each thirty feet long in a thirty foot silo will be erected in place on the foundation and held in place by any suitable false work. The staves will then be assembled on the foundation. The first stave will be fastened to the door post by the dowel pins 10 shown in Figure 2. Other staves will be added continuously, around the ring of the foundation from each door post and the staves that meet at the back will be sprung together and locked with the dowel pins as they are sprung. The staves will be erected to the full height as the structure progresses around the silo and the staves are locked with the dowel pins. At the bottom the staves will be held in position by the first hoop which will be placed about six inches above the bottom of the stave. All of the hoops will be bent in the shop to the right curve. After a few staves have been erected on each side of the door post, a second hoop will be put in place about one half way up the silo and a third hoop will be put in place near the top of the silo. These hoops will be held in place at or near the back with suitable false work. As the assembling of the staves progresses the dowel pins will hold the staves in place for all practical purposes and then the remaining hoops and couplings and turnbuckles can be put on for the purpose of tying the complete structure together.

It will be understood that suitable holes will be bored in the door posts for the reception of the ends of the hoops and that the straps 7 and brackets 8 will anchor the bottom of the staves to the studs 4 in the foundation.

When the hoops are passed through the door posts, the nuts 28a and 28b are threaded onto the ends of the hoops.

It will also be understood that the links 37a and 37b will be placed on the hubs of the turnbuckles and the turnbuckles will be engaged with the hoops for the purpose of drawing the hoops into place.

The doors will then be hung from the links and the links will be tied together by the angle irons to form the steps or rungs of the ladder.

The channel will then be built on top of the staves, and the sections of the dormer roof will then be assembled on top of the channel.

The usual staples will be used at intervals to further anchor the hoops to the staves so that they stay in a horizontal line.

In Figure 5 I have shown the top of the concrete base 75

sloped at an angle of 45° and the bottom of the staves are beveled almost to correspond. This angle of the base may be of any greater or less angle and may be even as small as 10° or 15° and may even be provided with a horizontal step or a series of steps cut therein on which can rest the bottom of the staves if they are cut at right angles at the bottom. These modifications will be easily understood by an inspection of Figure 5.

I claim:

1. In a silo, the combination of a base and upright staves, hoops surrounding the staves and holding them together, said hoops having threaded ends, a doorway in said silo having a post on each side thereof circumferentially abutting adjacent staves, the ends of said hoops extending through said posts, nuts on the threaded ends of said hoops bearing on the facing sides of said posts, a turnbuckle coupling the free ends of said hoops, said posts being beveled on their substantially entire inner sides, doors extending across said doorway, each of said doors having beveled edges adapted to make contact with the beveled sides of the posts whereby the spacing between said posts varies.

2. In a silo, the combination of a base and upright staves, hoops surrounding the staves and holding them together, said hoops having threaded ends, a doorway in said silo having a post on each side thereof in circumferential abutting relation to an adjacent stave, said posts being radially thicker than said staves and projecting radially outward of said staves, the ends of said hoops extending through said posts, nuts on the threaded ends of said hoops bearing on said posts, a turnbuckle threadedly coupling the free ends of said hoops, said turnbuckle having a single offset central connecting portion on one side, doors in said doorway, cleats extending up and down on the outside of each door, said cleats extending between the free ends of said hoops and in the space provided by the turnbuckle offset portion, C-shaped links, the upper ends of which engage the respective ends of the turnbuckles, the other ends of which make engagement with slots in the side of the door whereby said door may be swung inwardly and upwardly to an upright inverted position, a hook for supporting the door in its inverted position.

3. In a silo, the combination of a base and upright staves, hoops surrounding the staves and holding them together, said loops having threaded ends, a doorway in said silo having a post on each side thereof circumferentially abutting adjacent staves, the ends of said hoops extending through said posts, nuts on the threaded ends of said hoops bearing on said posts, a turnbuckle coupling the free ends of said hoops, said turnbuckle having a single offset central connecting portion on one side, doors in said doorway, cleats extending up and down on the outside of each door, spaced C-shaped links, the upper end of each of which is pivoted on the opposite ends of the turnbuckle, the other end of which links couple spaced slots in the side of the cleats of said door by which engagement the link can support the door in an upright or elevated inverted position, a hook for supporting the door in its inverted position, an angle iron fastened between the links of each door at the corners thereof which irons serve as the rungs of a ladder when the door is in its upright position.

4. In a silo, the combination of staves circularly arranged and a doorway having posts abutting said staves along one side and with their radially inwardly facing backs beveled, doors beveled on their front sides to nearly correspond with the bevels on the back of the posts so that the outer edges of the doors can make close contact with the bevels on the backs of the posts irrespective of variations in the spacing between posts, means for circumferentially compressing said staves through said posts, and means for maintaining the diameter of said staves fixed.

5. In a circular silo, a plurality of staves arranged

in a C to form a door, tension means extending around said staves from opposite sides of said door, means for maintaining said staves in a fixed circle, and a rigid annular inverted roof-supporting channel positioned on the upper ends of said staves, with the inner and outer flanges closely embracing said staves, and articulated means vertically extending connecting said staves with said channel, whereby said staves may move circumferentially with respect to the channel.

6. A silo comprising, in combination, a base, upright staves, said staves forming a C-shaped wall providing a door opening, a post on each side of said door opening abutting the end staves of said C-shaped wall, hoops surrounding said staves and having threaded ends extending through said posts, nuts on said ends adapted to bear against the facing sides of said posts, a turn buckle joining said threaded ends, said turn buckle having threaded end portions, and a single connecting bar portion extending between said end portion and laterally disposed in respect to the threaded ends of said hoops, said posts having beveled inside faces extending over the circumferential thickness of said posts, and doors for said door opening having beveled edge faces adapted to engage said beveled post faces in a radial outward direction.
